UNITED STATES PATENT OFFICE

92,290

DESIGN FOR A GLASS ALPHABET HAVING MIRROR FACES FOR FORMING MONO- GRAMS OR THE LIKE

Michael Chernow, Brooklyn, N. Y.

Application October 6, 1933, Serial No. 49,412

Term of patent 3½ years

To all whom it may concern:

Be it known that I, MICHAEL CHERNOW, a citizen of the United States and residing at Brooklyn, in the county of Kings and State of New York, have invented a new, original, and ornamental Design for a Glass Alphabet Having Mirror Faces for Forming Monograms or the like, of which the following is a specification, reference being had to the accompanying drawing, forming part hereof, and in which

Fig. 1 is a plan view of a molded glass alphabet for forming monograms or the like, showing my new design, and

Fig. 2 is an enlarged transverse sectional view on the line 2—2 of Fig. 1.

The individual characters have their extreme edges bounded by a square, with relatively small notches communicating with the sides of the bounding squares to afford massive characters.

I claim:

The ornamental design for a glass alphabet having mirror faces for forming monograms or the like, substantially as shown and described.

MICHAEL CHERNOW.
